UNITED STATES PATENT OFFICE.

FRANK E. BRIXTUS, OF MANITOWOC, WISCONSIN, ASSIGNEE OF ONE-HALF TO GEORGE F. BRÜNNER, OF MANITOWOC RAPIDS, WISCONSIN.

ELECTRICALLY-OPERATED HAMMER.

1,110,285.

Specification of Letters Patent.

Patented Sept. 8, 1914.

Application filed April 19, 1913. Serial No. 762,320.

To all whom it may concern:

Be it known that I, FRANK E. BRIXTUS, a citizen of the United States, residing at Manitowoc, in the county of Manitowoc and State of Wisconsin, have invented certain new and useful Improvements in Electrically-Operated Hammers, of which the following is a specification.

My invention relates to hammers, for flattening the heads of rivets or the like, or for doing similar or analogous work, and has particular reference to apparatus of this character, embodying a striking element which is reciprocated by a plurality of solenoids, alternately connected and disconnected with and from a source of current by novel means.

An important object of my invention is to provide apparatus of the above mentioned character, which is readily portable so that the same may be moved about from place to place in a shop or the like.

A further object of this invention is to provide a hammer of the above mentioned character, the reciprocatory or striking element of which is capable of being operated or driven at a very high speed in a continuous manner, without inconvenience to the operator or in any way interfering with the portability of the apparatus.

A further object of this invention is to provide apparatus of the above mentioned character including means which are wholly mounted upon the apparatus, in the embodiment of an electric motor operated switch means for continuously and expeditiously energizing and deenergizing the solenoids or electrical means included therein.

A further object of my invention is to provide electrically operated means, to move the reciprocatory striking element in the striking direction, with a much greater force, than when such means moves it in the returning direction.

Other objects and advantages of this invention will be apparent during the course of the following description.

In the accompanying drawings forming a part of this specification and in which like numerals are employed to designate like parts throughout the same, Figure 1 is a central longitudinal sectional view through the hammer apparatus, the circuits being shown diagrammatically, for the purpose of illustration, Fig. 2 is a transverse sectional

view taken on line 2—2 of Fig. 1, and, Fig. 3 is an end view of the rolls included in the switch means.

In the drawings, wherein for the purpose of illustration is shown a preferred embodiment of my invention, the numeral 4 designates a shell or casing, forming the body portion of the hammer apparatus, and preferably formed of aluminum, brass, or other non-magnetic material. This shell or casing 4 comprises an enlarged cylindrical portion 5, provided at its ends with tapering extensions 6 and 7, decreasing in diameter outwardly. Formed upon the tapering extensions 6 and 7 are contracted sleeves 8 and 9 respectively. Removably mounted within the sleeve 8 is a tool 10, which is free to reciprocate therein. This tool is provided at its outer end with a head 11, as is customary. The free end of the sleeve 9 is preferably internally screw-threaded for receiving a screw-threaded plug 12, rigidly connected with a loop-handle 13, as shown.

Rigidly mounted within the enlarged cylindrical body portion 5 is a striking solenoid 14. Rigidly mounted within the sleeve 9 is a returning solenoid 15. Attention is called to the fact that the diameter of the striking solenoid 14 is much greater than that of the returning solenoid 15 while the length of the returning solenoid 15 is greater than the length of the striking solenoid 14. The solenoid 14 is more powerful than the returning solenoid 15, the total flux within the solenoids varying of course with the ampere turns, cross-sectional area of the cores and with the distribution of the flux through the cores. By having the striking solenoid 14 of greater diameter and shorter than the returning solenoid 15 and otherwise constructed to have a greater flux than the solenoid 15, the solenoid 14 will move the reciprocatory core forwardly with greater force and rapidity while the solenoid 15 will move the same in a reverse direction at a reduced speed and force.

The numeral 16 designates a common reciprocatory striking element provided with an enlarged core 17, which is disposed near and spaced from the forward end thereof and preferably cast integral with the striking element or rod 16. This core 17 is movable into and out of the solenoid 14. The striking element or rod 16 is provided at its rear end with a core 18, preferably cast

integral therewith, which is movable into and out of the returning solenoid 15. Attention is called to the fact that the core 17 is of greater diameter than the core 18 while the core 18 is longer than the core 17. By this construction I have found that the striking solenoid 14 with its increased diameter will move the striking element or rod 16 forwardly with considerable force to impinge against the tool 10, while the returning solenoid 15 with its contracted diameter and increased length will move the striking element or rod 16 in an opposite direction sufficiently quickly, without such a high degree of force. It is not only unnecessary but disadvantageous to move the rod or striking element 16 upon its return movement with the same degree of force as the same is being moved to impinge against the tool 10, since by exerting too much force upon returning the striking element, unnecessary jars and strains would be transmitted to the casing and other parts of the apparatus. I have found that my construction completely overcomes this disadvantage without unduly reducing the rapidity at which the striking element or rod 16 may be reciprocated.

The numeral 19 designates a source of current, connected with feed and return wires 20 and 21. Connected with the feed wire 20 is a wire 22, which is connected with a brush 23, adapted to engage with a metallic contact 24, carried by an insulating roll 25 and extending diametrically thereof. Arranged diametrically opposite the brush 23 is a co-acting brush 26, to engage with the metallic contact 24 and connected with a wire 27. This wire is connected with one end of the winding of the solenoid 14, the other end of which is connected with a wire 28, which is connected with the return wire 21. The feed wire 20 has a wire 29 connected therewith, which is connected with a brush 30, adapted to be engaged by a metallic contact 31 carried by an insulating roll 32 and extending diametrically thereof. An oppositely arranged brush 33 is adapted to be engaged by the metallic contact 31 and is connected with a wire 34. This wire 34 is connected with one end of the winding of the returning solenoid 15, the opposite end of which is connected with a wire 35, which is connected with the return wire 21. The insulating rolls 25 and 32 are rigidly mounted upon a rotatable shaft 36.

The numeral 37 designates a suitably small electric motor, which is rigidly mounted upon the sleeve 9. This electric motor has its armature connected with the shaft 36, which constitutes the armature shaft. A particular advantage is gained in the provision of the electric motor for continuously rotating the shafts 36 carrying the switch means, to wit, the fact that the entire apparatus may be readily moved

from place to place, that is from one part of a room to the other. If the shaft 36 was provided with a pulley, to be engaged by a belt which was driven by a prime mover located at a distance in the shop or room, it is obvious that the apparatus as a whole would not be portable. The switch means and the electric motor are preferably enclosed by a housing or box 38. One pole of the motor 37 is connected with a wire 39, which is connected with the feed wire 20 and the opposite pole of the motor is connected with a return wire 40, connected with the return wire 21. Connected in the common return wire 21 is a switch 41, which is preferably mounted upon the handle 13, owing to the convenience with which the same can be operated when so arranged. Connected in the wire 39, which is the feed wire of the motor 37, is a rheostat 42, for controlling the speed at which the motor operates, independently of the supply of current to the solenoids.

The operation of the apparatus is as follows: The operator holds the loop-handle 13 in his right hand and the sleeve 9 in his left hand, whereby the tool 10 may be moved into engagement with the head of the rivet or other piece of work. The switch 41 is then operated to close the circuit, whereby the motor 37 will be set into operation, the speed at which the same operates being controlled by the rheostat 42. When the shaft 36 is moved to the position so that the two brushes 23 and 26 engage the metallic contact 24, a circuit will be closed for energizing the striking solenoid 14, whereby the striking element or rod 16 is moved forwardly with considerable force, to impinge against the tool 10. In this closed circuit current flows from one side of the source of current 19, through wire 20, wire 22, brush 23, metallic contact 24, brush 26, wire 27, solenoid 14, wire 28, and through wire 21 back to the opposite pole of the source of current. The metallic contact 24 is preferably arranged at a right angle with relation to the metallic contact 31, whereby they are alternately brought into engagement with their respective contact brushes. When the metallic contact 31 engages the brushes 30 and 33 a circuit is closed for energizing the returning solenoid 15. In this circuit current flows from one pole of the source of current 19 through wire 20, wire 29, brush 30, metallic contact 31, brush 33, wire 34, return solenoid 15, wire 35, and through wire 21 back to the opposite pole of the source of current. It is thus seen that the solenoids 14 and 15 are alternately energized and deenergized to reciprocate the striking element or rod 16. I have found that by the provision of the two solenoids, in combination with the electric motor for driving the contact means, such striking element or

rod may be reciprocated with great rapidity. The striking solenoid being more powerful will move the striking element or rod 16 forwardly with considerable force, while the returning solenoid 15, being of a less power, will move the striking element or rod 16 in a reverse direction, sufficiently quickly without near as much force, whereby the apparatus is not subjected to undue shocks and jars upon the return movement of the striking element or rod 16. When the switch 41 is closed the current is supplied directly to the solenoids 14 and 15, while the supply of current to the motor 37 is controlled by the rheostat 42, whereby the same will be made to operate at a desired speed.

It is to be understood that the form of my invention herewith shown and described is to be taken as a preferred example of the same, and that certain changes in the shape, size and arrangement of parts may be resorted to without departing from the spirit of the invention or the scope of the subjoined claim.

Having described my invention, I claim:—

In apparatus of the character described, a tubular casing adapted to be conveniently handled by a single operator and having a central enlarged portion provided with laterally contracted forward and rear end

portions, the forward laterally contracted end portion being adapted to be held in one hand of the operator, a reciprocatory tool mounted within the forward laterally contracted portion, a relatively strong solenoid winding disposed within the central enlarged portion of the tubular casing, a relatively weak solenoid winding arranged within the rear laterally contracted end portion of the tubular casing, a reciprocatory core common to both solenoid windings to engage the tool, an electric motor mounted upon the rear end portion of the tubular casing with its armature shaft extending longitudinally of and parallel with the laterally contracted rear end portion, circuits connected with the solenoid windings, circuit opening and closing devices connected in the circuits and with the armature shaft for rotation thereby, means for connecting said motor in the circuits, and a transverse handle connected with the free end of the rear laterally reduced end portion of the tubular casing.

In testimony whereof I affix my signature in presence of two witnesses.

FRANK E. BRIXIUS.
